UNITED STATES PATENT OFFICE.

HARRY J. BECK, OF PHILIPSBURG, PENNSYLVANIA, ASSIGNOR OF ONE-HALF
TO CLAUDE GETTE, OF SAME PLACE.

DESIGN FOR AN ICE-CREEPER.

SPECIFICATION forming part of Design No. 32,300, dated February 27, 1900.

Application filed December 30, 1899. Serial No. 742,161. Term of patent 31 years.

To all whom it may concern:

Be it known that I, HARRY J. BECK, a citizen of the United States, residing at Philipsburg, in the county of Centre and State of Pennsylvania, have invented and produced a certain new and original Design for Ice-Creepers; and I do declare the following to be a full, clear, and exact description of the invention, such as will enable others skilled in the art to which it appertains to make and use the same.

The invention relates to a new and original design for an ice-creeper; and it consists of a design of the shape and configuration shown in the accompanying drawings, in which—

Figure 1 is a top plan view. Fig. 2 is a side view, and Fig. 3 is an end view.

The leading features of the design comprise the side bars 1 and 2, one set of ends of which are bowed to form loops 3 and 4, while the other set of ends diverge outwardly and form

arms 5, 6, 9, and 10, the junctions of which are formed with inwardly-projecting lugs 7 and 8. The arms 5, 6, 9, and 10 extend outwardly at approximately right angles to a straight line drawn between the side bars 1 and 2, and the arms 9 and 10 terminate in forwardly-projecting arms 11 and 12, which have inwardly-projecting parallel arms 13, the ends of which terminate in downwardly-projecting prongs 14.

What I claim is—

The design for an ice-creeper, as herein shown and described.

In testimony whereof I have hereunto set my hand in presence of two subscribing witnesses.

HARRY J. BECK.
